UNITED STATES PATENT OFFICE.

ARTHUR R. ROBERTSON, OF SOMERVILLE, MASSACHUSETTS.

MAGNETIC TACK-HAMMER.

SPECIFICATION forming part of Letters Patent No. 352,070, dated November 2, 1886.

Application filed May 22, 1886. Serial No. 202,958. (No model.)

To all whom it may concern:

Be it known that I, ARTHUR R. ROBERTSON, of Somerville, in the county of Middlesex and State of Massachusetts, have invented 5 certain new and useful Improvements in Magnetic Tack-Hammers, of which the following is a specification.

My invention relates to hammers, and particularly to what are known as "magnetic" 10 hammers—that is, that class of hammers having heads charged with magnetism for the purpose of attracting nails or tacks to the peen thereof and holding the same by the head in position thereon to be "set" or driven.

15 My invention has for its object to provide a hammer of greater magnetic power than hammers of that class as heretofore constructed, so that shingle-nails or nails of considerable size can be set thereby, and also so that tacks or 20 small nails can be held with greater security and driven with greater certainty and precision.

To the foregoing ends my invention consists in constructing the head of the hammer in the 25 form of a horseshoe-magnet in such manner that the poles of the magnet will form one of the peens or faces of the hammer, all as hereinafter described, and subsequently set forth in the claims.

30 Of the drawings hereto annexed and forming a part of this specification, Figure 1 represents a side view of a hammer constructed in accordance with my invention. Fig. 2 represents a side view of a hammer-head embodying my invention and provided with a tack-drawing claw on the driving end. Fig. 3 represents a view of a hammer-head similar to that shown in Fig. 2, showing a claw of somewhat different form and construction. Fig. 4 35 represents a modification of the invention, hereinafter referred to.

The same letters of reference indicate the same parts in all the figures.

In the drawings, *a* represents the hammer 45 head, and *b* the handle.

c indicates the tack or nail setting peen, and *d* the driving-peen.

As is shown in Figs. 1, 2, and 3, the head 50 of the hammer is divided from a point between the driving-peen *d* and the eye for the handle to the setting-peen *c*. A hammer-head thus constructed, when charged with magnetism,

forms a substantial horseshoe-magnet, of which the driving end *d* constitutes the back or neutral end and the peen *c* the poles. The two 55 parts at the end *c* do not come in contact with each other, but are brought quite close together, so that the slit or bifurcation dividing them does not militate against this face as a means for driving a nail or tack; and 60 although I have termed the end *c* the "setting-peen"—that is, the peen designed to set or start the nail at the point where it is to be driven—it may be employed for driving as well, though when a broader face is desired 65 for this latter purpose the end *d* may be used.

My improved hammer-head is designed to be permanently charged with magnetism, and as thus constituted will have sufficient power to attract nails of very large size, so as to hold 70 the heads thereof on the peen *c* with sufficient force to permit them to be set with certainty and precision.

I am aware that magnetic hammers have heretofore been constructed; but so far as I am 75 aware such contrivances have been entirely confined to hammers constructed as "bar-magnets." My invention differs from these in that my hammer-head is formed as a horseshoe-magnet, which form, as is well known, is capable 80 of possessing much greater magnetic power than a bar-magnet, and hence I am able to hold and control tacks or nails with greater certainty, as also nails of greater size and weight, than has been possible with magnetic 85 hammers as heretofore constructed, or constructed as bar-magnets.

A tack or nail held by the head upon the peen *c* may be driven "home" with a single blow, or be first set with a light blow or "tap" 90 and afterward driven to place, or it may be set with the peen *c* and driven with the head *d*. This latter mode of procedure is usually preferred with "shingle-nails" and nails of larger size and weight. In some instances I 95 form a claw on the driving end, and construct this feature to meet the wants of particular cases, Figs. 2 and 3 showing heads provided with "claws" of slightly different forms.

In Fig. 4 I have shown a hammer-head constructed as a compound horseshoe-magnet—that is, a magnet composed of two or more magnets secured together. This form of magnet is more powerful than the single horse-

shoe-magnet, though for ordinary purposes I have found the solid simple horseshoe-magnet to have sufficient power. When constructed as a compound magnet, it may be preferable to 5 form the eye for the handle in the neutral point or end above the connecting-point of the two arms constituting the poles.

The hammer may be constructed of any size and shape so long as the horseshoe character 10 thereof is preserved, it being desirable in all cases to have the arms of the magnet as long as is consistent with strength and convenience, as a bow having long arms is capable of being made a stronger magnet than a bow with short- 15 er arms.

Having thus described my invention, I claim—

1. A magnetized hammer-head having its body divided or bifurcated to constitute a sub- 20 stantial horseshoe-magnet, as set forth.

2. A magnetized hammer-head having its body divided or bifurcated for the greater portion of its length to constitute a substantial horseshoe-magnet in which the poles form one peen and the back or neutral end the other 25 or another peen, as set forth.

3. A horseshoe-magnet constructed as a hammer-head, in which the poles of the magnet comprise the setting-peen and the back or neutral end constitutes the driving-peen, as 30 set forth.

In testimony whereof I have signed my name to this specification, in the presence of two subscribing witnesses, this 10th day of May, 1886.

ARTHUR R. ROBERTSON.
